COMBINED HOBBYHORSE AND BICYCLE

John P. Dondelinger, 9138 Greenwood Ave.,
Des Plaines, Ill.

Filed May 18, 1959, Ser. No. 55,964

Term of patent 14 years

(Cl. D34—15)

Fig. 1 is a front perspective view of a combined hobbyhorse and bicycle showing my new design;

Fig. 2 is a side elevation of the combined hobbyhorse and bicycle;

Fig. 3 is a top plan view;

Fig. 4 is a front elevational view; and

Fig. 5 is a rear elevational view.

I claim:

The ornamental design for a combined hobbyhorse and bicycle, as shown.
